(57) **CLAIM**

The ornamental design for a training pad, as shown and described.

DESCRIPTION

FIG. 1 is a front view showing a first embodiment of my new design for a training pad consisting of the combination of a left end portion, an intermediate portion and a right end portion;

FIG. 2 is a left side view of FIG. 1;

FIG. 3 is a top plan view of FIG. 1; and,

FIG. 4 is a front perspective view showing a second embodiment of my new design consisting of a full length training pad. The surface portions obscured by the trainee in broken lines form no part of the claimed design.

The broken line showing of the trainee and surrounding environment in FIG. 4 are for illustrative purposes only; and form no part of the claimed design.
